UNITED STATES PATENT OFFICE.

RICHARD COLE, OF BURBANK, CALIFORNIA.

OIL-SPASH LINING FOR PISTONS.

Application filed May 24, 1922. Serial No. 563,323.

This invention relates to the protection of lubricating oil in the crankcase of internal combustion engines.

It is a well known fact that in internal combustion engine operation, lubricating oil destruction is largely due to heat exposure. Motor manufacturers, engineers, designers, experts, mechanics and all those who are well versed and skilled in the art of building and operating internal combustion engines, have neglected and failed to protect the lubricating oil from the destructive heat present in the inside of the piston and on the walls thereof, and more particularly the under surface of the piston head.

The oil thus continuously exposed is ruined by being heated, cracked, burned, cooked, fried, vaporized, carbonized and wasted in consequence, causing rapid deterioration, a high rate of sedimentation, becoming less viscous, thereby lowering its lubricating quality. Therefore, the result is rapidly worn parts, such as pistons, piston rings, cylinders, and bearings.

As the working temperature of the piston head is about 900 to 1100 degrees Fahrenheit, it will readily be seen that this heat is the principal cause of a chemical and a physical change in the lubricating oil.

The vaporizing loss is caused by this heat, and therefore, a residual condition is reached more rapidly than would be the case were this condition eliminated as will be herein-after set forth.

An object of this invention is to provide means that will preclude oil from washing over the inside surface of the piston of an internal combustion engine, and more particularly the upper inside portion thereof.

Another object is to provide a light drawn sheet metal lining of suitable shape fixed in the piston wherein the oil will be prevented from coming in contact with and be insulated from the highly heated under surface of the piston head and inside of the piston skirt of an internal combustion engine piston.

Another object is to provide an attachable lining adapted to be placed in the inside of a piston of an internal combustion engine supported by the wrist-pin and the lower edge of the piston skirt.

A further object is to provide a lining held in the piston of an internal combustion engine by the wrist-pin thereof and further

supported by the rim fitting a portion of the piston skirt, thereby forming an air chamber between the inside walls of the piston and the lining.

With the above and other objects in view the invention consists in the novel construction as herein described and claimed, and illustrated in the accompanying drawings, in which:

Figure 1 is a vertical cross section of an internal combustion engine of the automotive type, showing the piston lining attached in position, in one form of piston.

Fig. 2 is an enlarged fragmentary vertical cross section as seen on the line 2-2 of Fig. 1, and at a right angle thereto.

Fig. 3 is a plan view of the attachable piston lining.

Fig. 4 is a side elevation of the attachable piston lining, partly broken away to clearly show the construction.

Fig. 5 is a perspective of the attachable piston lining.

Fig. 6 is a vertical cross section of another form of piston assembly with the lining in place.

Fig. 7 is a vertical cross section as seen on the line 7-7 of Fig. 6 and at a right angle thereto.

Fig. 8 is a perspective of a modified form of lining the side walls of which are flattened.

Fig. 9 is a perspective of another modified form of lining, the side walls of which form a cone.

Fig. 10 is a fragmentary perspective showing one of the radial drain ducts in the flange of the lining.

Fig. 11 shows a section of a modified form of piston having a lining cast integral therewith.

More specifically, an attachable piston lining 10, is fixed in a piston 11, of an internal combustion engine 12 (as shown in Fig. 1) in which the piston 11 is reciprocally mounted in the cylinder 13, and oscillatably secured to a connecting rod 14, by a wrist-pin 15, the connecting rod 14 being rotatably bolted to a crank pin 16 of the crank-shaft 17 carried in the crankcase 18 to which the cylinder 13 is fixed.

As the piston 11 moves downwardly the crankshaft 17 is revolved, whereupon it strikes a bath of lubricating oil (not shown) in the crankcase 18 which is splashed in all

directions. At this time, a great amount of this oil is splashed against the lining 10 in the piston 11 as it is now near its lower position in the cylinder 13 and near the top 19 of the crankcase 18 at the time of the fullest agitation of the lubricating oil.

By reason of the lining 10 fixed into the piston 11 the lubricating oil will be prevented from washing over the highly heated 10 inside surface 20 of the piston 11. The oil being arrested by the lining 10 will therefore drain to the crankcase without splashing in the piston 11.

Referring to Fig. 2 the lining 10 is shaped 15 so as to slide between the inner faces 21 of the wrist-pin bosses 2—2.

In Figs. 3, 4, and 5 I have shown the attachable lining 10 apart from the piston 11 so that it may be described in detail. The 20 side wall 23 is cylindrical in shape and forms a dome 24 at its upper end, and the lower portion 25 is open; there being an annular flange 26 formed to conform and fit the bead or rim 27 of the piston skirt.

25 As stated before, the upper portion is formed to fit between the wrist-pin bosses 22, thereby making oppositely disposed faces 28, the said faces being pierced in the central portion thereof making openings 29 of 30 a size to allow the entrance of wrist-pin 15, so that when the lining 10 is pushed upwardly into piston 11, the openings 29 will align with the openings 30 in the wrist-pin bosses 22 so as to permit the wrist-pin 15 to 35 enter and engage connecting rod 14 for assembly therewith, said openings 29 in the lining 10 being a close fit on the wrist-pin 15. Also the side faces 28 fitting closely the faces 21 of the wrist-pin bosses 22 allow for 40 the usual and conventional clearance for the connecting rod end 31 which is necessary in engine construction.

The lower portion 25 and flange 26 fitting 45 the rim 27 of the piston skirt and the openings 29 fitting the wrist-pin prevents any movement of the lining 10, as it moves as though integral with the piston 11.

Any oil that may work past the lining 10 at the wrist-pin openings 29 from the inside 50 of the lining 10 or from the openings 30 to the chamber 32 between the lining 10 and the inside of the piston 11 will not come in contact with the under surface 20 of the piston ring belt, (which surface constitutes 55 the highly heated portion on the inside of the piston) but will travel downwardly and drain between and past the rim 27 of the piston 11 and flange 26 of the lining 10 in small radial ducts 33 (shown in Fig. 10) 60 formed on the flange portion 26 to carry off any oil present, so that this small amount of oil will not be trapped and held in the lower cavity of the chamber 32 between the lining 10 and piston skirt.

65 The ducts or vents 33 also provide air pas-

sages for the free circulation of air to and from the crank case, which air will have a cooling effect on the piston so the head thereof will not overheat and cause pre-ignition in the combustion chamber. If these ducts 70 were not provided the piston would overheat.

As shown in Fig. 2 small beads 34 may be formed in the lining 10 after said lining is placed in the piston 11 to more firmly set 75 the lower portion 25 of the lining 10 against the rim 27 of the piston skirt.

A drip point 35 is formed in the top of the dome portion 24 of the lining 10 so that oil splashed thereon will drip to the oil feed opening 36 in the end 31 of the connecting rod 14 to lubricate the wrist-pin 15 as in this form of piston assembly the wrist-pin is held in place by a set screw 37 in the piston 11 and is free in the connecting rod. With this construction an opening 38 is made 85 in the lining for the use of this set screw.

In the construction shown in Figs. 6 and 7 the wrist-pin 39 is held in the connecting rod 40 and is free in the wrist-pin bosses 41 in the piston 42 and therefore the drip point 35 and set screw opening 38 are not necessary.

The modified lining 43 and 44 shown in 90 Figs. 8 and 9 can be used in a form of piston assembly wherein a ring is so placed that it will encompass the ends of the wrist-pin thereby keeping it in place; in this construction the connecting rod is free on the wristpin.

In Fig. 11 I have shown a modified piston 95 having a lining formed integral with the piston skirt and the ducts or vents 33 drilled for the purpose stated herein.

The present conventional pistons now in use will not have to be altered as this piston lining can be made to slip in place and held without the use of fastenings.

In keeping the oil away from the inside 100 walls of the piston carbon scale cannot form thereon and drop into the oil supply in the crankcase, subsequently working into the bearings and oil pump and causing trouble at these points.

In placing my lining in the piston (as shown in the drawings) I prevent the oil from splashing on the hot inner surface of the piston head and walls of the piston, confining the oil splashed upwardly to the inside of the lining and to its proper place on the cylinder walls.

The temperature of the oil will not then rise above the normal heat from the bearings and upper crankcase. The oil will remain durable and efficient for a longer period of time retaining to an appreciable degree its original state of viscousness, moreover, it will also have a greater resistance to the heat of 2700 degrees Fahrenheit temperature, obtained at the time of explosion in the 115 120 125 130

combustion chamber, as it has not been pre-heated as is now the case in this type of engine.

At present, all things considered, the oil working on the cylinder walls has a better chance than the oil being splashed into the inside of the piston, that is: the greater part of the oil that burns on the combustion chamber wall space passes off while the oil continually splashed on the inside of the piston becomes heated and burned to a certain extent thereby lowering its value and thereafter draining into the crankcase to mix with the oil supply contained therein. The oil, baffled as disclosed will be presented on the combustion chamber walls in better condition to resist the intense combustion heat maintained. The oil protecting lining on account of its being entirely out of contact with the piston head or the piston ring belt and its relatively small amount of contact had with the piston at the comparatively cool rim of the piston skirt, and with the air chamber thus formed insures a practical insulation from high temperature for the oil.

From the foregoing it is apparent that continuous chemical reactions within the oil due to heat are inevitable and each time the new supply of oil is placed in the crankcase it is subject to rapid changes and is partially dissipated from contact with the old oil remaining in the crankcase that has been to a great extent burned out, therefore, by protecting the lubricating oil from the destructive heat of the inner surface of the piston a better working condition for the oil is obtained thus prolonging its life and resulting in less wear to the surfaces of the working parts.

It is logical to conclude, therefore, that the heating, burning and destruction of the lubricating oil in the crankcase depends upon the operating temperatures of motor parts with which it comes in contact, particularly the highly heated lower surface of the piston head.

While I have shown the preferred form of construction I do not limit or restrict the invention to the exact details shown, as various modifications may be made without departing from the spirit of the invention as claimed.

I claim:

1. A splash lining for a piston adapted to be placed therein, said splash lining provided with air circulating and oil drainage ducts formed in the lower portion thereof, said lower portion of said lining having contact with the skirt of a piston when placed therein.

2. In combination with an internal combustion engine piston provided with a wrist pin, means comprising a lining adapted to prevent oil from splashing internally of said piston, and ducts formed in said lining, to extend outwardly around the lower edge of the piston to allow air to circulate therein and oil to drain therefrom.

3. In combination with an internal combustion engine a piston comprising a head, a skirt depending therefrom, a lining forming a splash preventing closure extending upwardly inside the skirt from the lower portion thereof so as to be spaced from the under side of the head and the skirt excepting the annular edge, and ducts formed in the lower portion of the piston where the skirt and lining contact with the openings of said ducts facing away from the direction of splashing oil, said piston and lining being perforated to permit the insertion of a wrist pin therethrough.

4. The combination with an internal combustion engine piston, of a separately formed member arranged within the piston and positioned so as to prevent oil from splashing onto the under side of the piston head and the inner surfaces of the skirt of said piston, and there being air circulation ducts formed in the lower portion of said oil splash preventing member, the openings of which are disposed away from the oil in the crank case of said engine.

5. The combination with an internal combustion engine piston, of a lining arranged within the piston to prevent oil from splashing therein, an annular flange formed on the lining to bear against the bottom of the piston skirt at an angle to the piston side walls, and combined air venting and oil drainage ducts formed in the lower portion of the lining and flange.

6. An oil splash lining for pistons comprising in combination, a piston, a wrist pin, a perforated dome shaped lining having the upper portion indented on opposite sides to clear the wrist pin bosses within the piston, said perforations formed to permit the insertion of the wrist pin therethrough after said member is placed in said piston for securing said member in place, said lining provided with an annular flange to fit the bottom edge of the piston, and air circulating and oil drainage ducts formed in the flange and lower portion of said member, so the openings of the ducts face outwardly near the outer surface of said piston to prevent oil from splashing on the inner side walls and bottom of the piston head.

RICHARD COLE.
